UNITED STATES PATENT OFFICE.

ALFRED H. SMITH, OF CHAPPAQUA, NEW YORK.

FREIGHT CAR.

Application filed March 11, 1922. Serial No. 542,994.

To all whom it may concern:

Be it known that I, ALFRED H. SMITH, a citizen of the United States, and residing at Chappaqua, in the county of Westchester and State of New York, have invented certain new and useful Improvements in Freight Cars, of which the following is a specification.

This invention relates to that general type of freight car and freight container illustrated in my Patent No. 1,407,593, issued February 21, 1922, wherein is shown the broad combination of a car having side and end walls and a series of freight compartment units arranged on said car within said walls, all of the units being independently secured on the car, and each unit being independently removable from the car without impairing the stability or security of the remaining units on the car.

My invention consists of an improvement in means of centering and securing each compartment on the car, and my invention consists further of the parts and combination of parts as will be hereinafter more specifically set forth.

In the drawings:

Figure 1 is a front elevation of one of the containers removed from the car,

Fig. 2 is a side elevation of a car with a plurality of containers mounted thereon, the containers and car being broken away,

Fig. 3 is an enlarged detail sectional view on the line 3-3, Fig. 2, looking in the direction of the arrows,

Fig. 4 is an enlarged detail perspective view of one of the lower corners of the containers showing the centering and securing element thereon, and

Fig. 5 is an enlarged detail sectional view on the line 5-5, Fig. 2, looking in the direction of the arrows.

The reference numeral 1 designates a car of any approved type having side walls 2, and end walls 3, said walls projecting a considerable distance above the sills of the car so that when the containers 4 are in position on the car, the bottom portion of the door 5 is below the top edge of the wall and in close proximity to the wall, whereby, as set forth in my said patent, it is impossible to open the door 5 to gain access to the interior of the container while the container is in position on the car.

The construction of the container may be of any approved type found desirable, and

therefore no detailed description will be given thereof.

Arranged at predetermined intervals and in pairs are series of centering and securing elements 6 on the inner face of the walls of the car. Preferably these centering and securing elements are formed from angle iron, the end portion of one of the flanges of the angle iron being beveled as at 7 which functions as a centering face to center the container as it is being lowered on to the car.

These centering and securing elements as will be seen from Fig. 2 are arranged in pairs converging toward the sills of the car, and secured to the walls of the car by suitable rivets 8, the next adjacent set of centering and securing means being similarly secured to the inner face of the walls of the car, the tops of the adjacent members of the sets substantially meeting as at 9 as shown in Fig. 2.

The containers are provided with centering and securing elements 10 secured to the container by rivets 11 and disposed at an angle to the containers corresponding to the angle of the securing element 6 and likewise converging toward the bottom of the container.

The securing and positioning elements 10 are made from angle iron and are beveled as at 12 at their lower ends, these bevels 12 coacting with the bevels 7 of the elements 6 to center the container as it is being lowered on to the car.

As the container is being lowered on to the car, it is centered by means of the bevels 7 and 12, respectively, and the securing elements 10 slide downwardly on the face of the securing elements 6 of the car and by reason of the angle of the two elements, the container is readily centered and guided to its proper position on the car, said elements also functioning to hold the containers against rocking and against longitudinal movement relative to the car.

It will be observed that the arrangement of the centering and securing elements on the car is such that one or more of the containers may be removed from the car without affecting the stability and security of the remaining containers on the car.

What I claim is:

1. The combination with a carrier having walls, and a plurality of containers adapted to be loaded on said carrier within said

walls, of registering abutments secured to the said walls and containers respectively and bodily disposed thereon at an angle to the vertical.

5. 2. The combination with a carrier having walls, and a plurality of containers adapted to be loaded on said carrier within said walls, of registering abutments secured to the said walls and containers respectively and bodily disposed thereon at an angle to the vertical, the initial engaging ends of the respective abutments being correspondingly beveled.

15. 3. A shipping container having abutments secured to the walls thereof and bodily disposed at an angle to the vertical.

4. A carrier having walls and abutments bodily secured to said walls at an angle to the vertical.

5. A shipping container having abutments secured to the walls thereof and converging toward each other toward the bottom of the container.

6. A carrier having walls and abutments secured to said walls and converging toward each other in the direction of the bottom or said wall.

7. The combination with a carrier having walls, and a plurality of containers adapted to be loaded between said walls, of registering abutments secured to the said walls and containers respectively and bodily disposed thereon at an angle to the vertical; said abutments each comprising an angle iron, one leg of which is beveled at one end.

30. 35. In testimony whereof I affix my signature.

ALFRED H. SMITH.
